R. R. HAGE

DOOR HOLDER

Filed August 24, 1923

Patented Feb. 9, 1926.

1,572,285

UNITED STATES PATENT OFFICE.

ROBERT R. HAGE, OF MINNEAPOLIS, MINNESOTA.

DOOR HOLDER.

Application filed August 24, 1923. Serial No. 659,109.

To all whom it may concern:

Be it known that I, ROBERT R. HAGE, a citizen of the United States, residing at Minneapolis, in the county of Hennepin 5 and State of Minnesota, have invented certain new and useful Improvements in Door Holders; and I do hereby declare the following to be a full, clear, and exact description of the invention, such as will enable 10 others skilled in the art to which it appertains to make and use the same.

My invention has for its object to provide an extremely simple and highly efficient door holder for swinging doors and the like, 15 and to this end it consists of the novel devices and combinations of devices herein-after described and defined in the claims.

In the accompanying drawings, which illustrate the invention, like characters indicate like parts throughout the several views.

Referring to the drawings:

Fig. 1 is an elevation of the improved door holder applied to a door frame and a 20 door hinged thereto for horizontal swinging movements, some parts being shown in section by means of broken lines;

Fig. 2 is a view partly in plan and partly in section taken on the line 2—2 of Fig. 1; 30 and

Fig. 3 is a detail view principally in section taken on the line 3—3 of Fig. 1, on an enlarged scale.

The numeral 4 indicates a door frame 35 having hinged thereto at 5 a horizontal swinging door 6 which may be for a garage or other building.

The improved door holder comprises a horizontal double toggle made up of end 40 links 7 and 8 and an intermediate link 9. Said end links 7 and 8 each comprise a single flat bar, and the intermediate link 9 comprises two laterally spaced flat bars, between which the inner ends of said end links 45 project and to which they are pivoted to permit buckling and straightening movements of the toggle in a vertical plane. A screw eye 10 anchors the outer end of the end link 7 to the top member of the door frame 4 with freedom to permit horizontal lateral swinging and vertical buckling and straightening movements of the toggle. The outer end of the end link 8 is hinged at 50 11 to a bracket 12 for horizontal swinging movement. This bracket 12 is secured to the inner face of the door 6, at the top thereof,

and arranged to hold the respective end of the toggle inwardly offset from a line extending between the hinges 5 and screw eye 10 when the door is closed and outwardly offset from said line when the door is open.

The toggle is arranged to be buckled by a downward movement and is stopped during its straightening movement by a transverse pin 13 secured to the downwardly offset 65 inner end 14 of the end link 7 and arranged to engage the lower edges of the bars comprising the intermediate link 9, as best shown in Fig. 2. This pin 13 is arranged to hold the links 7 and 8 with their pivotal 70 connection slightly beyond a dead center and thereby lock the toggle against buckling movement.

A coiled spring 15 has one of its ends anchored at 16 to a depending lug on the link 75 8 close to its hinge 11, and its other end is attached to the offset end of the link 8 at a point below the stop pin 13 and is under strain, when the door is open, to hold the links 7 and 9 with their pivotal connection 80 beyond a dead center.

To vary the operative length of the toggle and thereby hold the door 6 in different open positions, the link 7 is made longitudinally adjustable by transversely separating the same and overlapping the inner ends thereof for sliding movement, the one upon the other, and securing said overlapped ends in different adjustments by a clamp 17. To keep the sections of the link 90 7 aligned, the same are provided with guide lugs 18 which overlap the upper and lower edges of the members of the link 7, as best shown in Fig. 2.

To afford means by which the toggle may 95 be buckled, there is attached to the intermediate link 9 a rope 19, the slack in which is normally taken up by a yielding holder or arm 20. One end of this arm 20 is attached to the bracket 12, and the other end thereof is provided with an eye through which the rope is free to slide.

As previously stated, the fact that the connection between the links 7 and 9 is beyond a dead center securely locks the toggle 105 and holds the door in an open position. By longitudinally adjusting the links 7, the door may be held in various open positions. To buckle the toggle and thereby close the door 6, it is only necessary to pull downward on the free end of the rope 19, and at 110 which time the arm 20 will yield and per-

mit the rope to give a direct pull on the intermediate link 9 against the tension of the spring 15. This spring 15 always exerts a force so that when the door is moved outward of a certain intermediate position, the force of the spring acting on the toggle will tend to straighten the same and open the door; and when the door is moved inward of said position, the force of said spring will tend to buckle the spring and close the door.

The above described door holder, in addition to its use for holding garage and other doors, is especially well adapted for holding the doors of covered delivery wagons and the like.

What I claim is:

1. A swinging door holder comprising a toggle having inner and outer end links, 20 an intermediate link, an offset bracket, said inner end link having means for attaching the same to a door frame, to which a swinging door is hinged, for compound swinging movement both in the direction of the swinging movement of said door and at right angles to such movement, said bracket having means for attaching the same to said door, the outer end link being hinged to the bracket for swinging movement in the 25 direction of the swinging movement of said door, said intermediate link being pivoted to the end links for movement at right angles to the swinging movement of the door, and a stop arranged during the straightening 30 movement of the toggle to position the pivotal connection between the inner end link and the intermediate link beyond a dead center.

2. The structure defined in claim 1 in further combination with a spring operative on the toggle when the door is fully open to hold the toggle beyond a dead center.

3. The structure defined in claim 1 in which said bracket is arranged to permit the door to swing from a closed position to an open position substantially parallel to said closed position.

4. The structure defined in claim 1 in which the bracket is arranged to move the 50 connected end of the toggle from one side to the other of a line extending from the hinges of the door to the attachment of the toggle with the door frame during the opening and closing movements of the door.

5. A swinging door holder comprising a double toggle having end and intermediate links, one of said end links having means for connecting the same to a door frame with 60 freedom to permit lateral swinging and buckling movements of the toggle, a bracket attachable to a swinging door hinged to the frame and to which bracket the other of said end links is hinged for lateral swinging movement, a stop for limiting the

straightening movement of the toggle and arranged to position the pivotal connection, between the end link that is attachable to a door frame and the intermediate link, beyond a dead center to lock the door open, and a spring tending to straighten the toggle, when the door is opened beyond a certain point, to continue the opening movement of the door and to hold the toggle against said stop to lock the door open.

6. A swinging door holder comprising a double toggle having end and intermediate links, one of said end links having means for connecting the same to a door frame with freedom to permit lateral swinging and 80 buckling movements of the toggle, a bracket attachable to a swinging door hinged to the frame and to which bracket the other of said end links is hinged for lateral swinging movement, a stop for limiting the straightening movement of the toggle and arranged to position the pivotal connection, between the end link that is attachable to a door frame and the intermediate link, beyond a dead center to lock the door open, and a spring tending to complete the buckling movement of the toggle when the door is moved beyond a certain point during its movement to a closed position, to continue the closing movement of the door.

7. The structure defined in claim 5 in which said spring also tends to complete the buckling movement of the toggle, when said door is moved beyond said point and during its movement to a closed position, to continue the closing movement of the door.

8. A swinging door holder comprising a double toggle having end and intermediate links, one of said end links having means for connecting the same to a door frame with freedom to permit lateral swinging and buckling movements of the toggle, a bracket attachable to a swinging door hinged to the frame and to which bracket the other of said end links is hinged for lateral swinging movement, a stop for limiting the straightening movement of the toggle and arranged to position the pivotal connection, between the end link that is attachable to a door frame and the intermediate link, beyond a dead center to lock the door open, and a spring anchored to the end link hinged to the door bracket and attached to the inner end of the other end link at a point offset in the direction of the buckling movement of the toggle and under strain to straighten the toggle when the door is moved beyond a certain point during the opening movement and to buckle the toggle when said door is moved beyond said point during its closing movement.

9. A swinging door holder comprising a toggle having one of the links arranged to be attached to a door frame, a bracket attachable to a swinging door hinged to said

frame and to which bracket another link of said toggle is attached, a stop for limiting the straightening movement of the toggle and arranged to position the pivotal connection between the links beyond a dead center to lock the door open, and an anchored spring attached to one of said links and under strain to straighten the toggle when the door is beyond a certain point during its opening movement and to buckle the toggle when said door is moved beyond a dead center during its closing movement.

In testimony whereof I affix my signature.

ROBERT R. HAGE.
